UNITED STATES PATENT OFFICE.

NEWTON K. BOWMAN, OF LAWRENCE, OHIO.

WATER-WHEEL.

SPECIFICATION forming part of Letters Patent No. 627,044, dated June 13, 1899.

Application filed July 5, 1898. Serial No. 685,114. (No model.)

To all whom it may concern:

Be it known that I, NEWTON K. BOWMAN, a citizen of the United States, residing at North Lawrence, in the county of Stark and State 5 of Ohio, have invented certain new and useful Improvements in Water-Wheels; and I do hereby declare the following to be a full, clear, and exact description of the invention, such as will enable others skilled in the art to 10 to which it appertains to make and use the same.

This invention relates to certain new and useful improvements in water-wheels, and particularly to horizontal wheels of the class known as "turbines;" and one object of the 15 invention is to provide an improved construction of race and manner of mounting such wheels, whereby that portion only of the circumference of the wheel which is being directly acted on is submerged, while the re- 20 turning or inactive portion thereof is arranged exteriorly of the race and out of contact with the water, thereby avoiding back pressure and retardation and attaining the full impulse of the flowing water.

25 Further objects are to provide a wheel of this character in which the bucket-carrying arms are pivoted to swing in a vertical plane and mounted on wheels or rollers adapted to traverse a trackway arranged in a novel man- 30 ner partially within and partially without the race, so that the temporarily inactive and returning buckets will be supported on a plane above the submerged buckets to relieve the arms of the latter of undue strain, to provide 35 improved means for adjusting and bracing the arms, and to generally simplify and improve the construction and increase the efficiency of water-wheels of this type.

With the accomplishment of these ends in 40 view the invention consists in certain novel features of construction, combination, and arrangement of parts, which will be herein- after more fully described, and specifically set forth in the appended claims.

45 In the drawings hereto annexed and forming a part of this specification, Figure 1 is a top plan view of a race and water-wheel constructed in accordance with my invention. Fig. 2 is a transverse section through the race 50 on line 2 2 of Fig. 1, showing the wheel and trackway in side elevation. Fig. 3 is a central vertical section through the race and

wheel on line 3 3 of Fig. 1. Fig. 4 is a cross-sectional view through the horizontal portion of the track, showing in broken lines the position to which the roller is shifted to release the bucket. Fig. 5 is a perspective view of one of the inclined ends of the track. Fig. 6 is a perspective view of one of the buckets. Fig. 7 is an inner side view of same, showing 60 the end wall thereof and the track in section. Fig. 8 is a longitudinal section of one of the braces. Fig. 9 is a detail perspective view of the adjustable coupling of one of the wheel-arms. Fig. 10 is a longitudinal sectional 65 view of same. Fig. 11 is a view similar to Fig. 1, but showing a modified construction; and Fig. 12 is a detail sectional view thereof.

Referring now more particularly to the drawings, wherein like letters of reference 70 designate corresponding parts throughout the several views, A and B represent the vertical, parallel, outer, and inner side walls of the race or water-channel, of which C is the head portion and D the tail portion, the said 75 walls being offset or deflected outwardly or in the same direction at the junction of said portions to form a segmental-shaped box or housing E for the acting circumferential portion of the horizontal water-wheel F. This 80 wheel consists of a hub g, mounted on a vertical shaft G, arranged on the exterior of the race, adjacent to the segmental portion of the side wall B thereof, and projecting outwardly from said hub are a series of equidistant radial arms H, which are connected thereto and 85 constructed as follows: Each arm is formed of two sections—a bucket-carrying section i and a coupling-section j, said coupling-section being pivoted at its inner end between 90 ears on the hub and the wheel-carrying section adjustably connected thereto by set-screws or bolts k, whereby the arm may be lengthened or shortened, as desired, to compensate for wear or to release the bucket carried thereby from the track in the manner more fully set forth hereinafter. In order to prevent undue lateral and longitudinal shifting or play of the wheel-carrying section of the arm under strain, the coupling-section is 95 preferably channeled or formed with side flanges l and provided on its upper face with corrugations or serrations adapted to engage with corresponding corrugations or serrations 100

on the under side or face of the inner end of the bucket-carrying section, as clearly shown in Fig. 10.

Bolted or otherwise detachably secured to the outer end of each radial arm is a bucket M, which may be of the usual or any preferred form. The end wall m of said bucket is preferably, however, stepped to form recessed faces $m' m^2$, and mounted on a stud or bolt projecting from the intermediate face m' is a wheel or roller n, which lies wholly within the plane of the upper wall portion m thereof. This wheel or roller is adapted to traverse the bottom of the race when the bucket is in operation and fully submerged and to run along a nearly circular track O when the bucket is out of operation and is being elevated on its return from the tail portion to the head portion of the race, where it is to be again submerged. The track is mounted upon suitable supports exteriorly of the race concentric with the shaft G, and the ends o o' are inclined and lead down into the race and terminate, respectively, adjacent to the points of junction of the outer segmental portion of the housing E with the wall A at the head and tail portions of the race, as clearly shown in Fig. 1. In cross-section the track is approximately of L form inclined inwardly, the vertical web thereof being provided with a flange p, which is relatively narrower than the horizontal track or rail proper portion q, and said rail portion with an inclined upwardly-projecting flange r. By reference to Figs. 3 and 7 it will be seen that the recessed face m' of the end wall of the bucket in traversing the track lies within the line of the said flange r and that the face m^2 bears against the outer face of said flange; also that the wheel or roller thereon has position immediately below the flange p. By this construction and arrangement of parts all liability of the bucket being forced upward and the roller dislodged from the track by the upward pressure of the water in descending and ascending the inclined ends of the track is avoided, and at the same time provision is made whereby leakage of the water around the end of the submerged bucket is reduced to the minimum. From the foregoing it will also be apparent that the parts may be adjusted to compensate for wear by means of the adjustable coupling of the radial arm, while the bucket may be readily and conveniently removed for repairs by simply disengaging the section i of the arm from its coupling-section j, pulling the bucket outwardly until its roller clears the flange p, and then lifting out said bucket. The flanges on the inclined ends of the track diminish in depth gradually to the extremities thereof in order that the bucket-rollers may run on and off the same with facility.

In operation each bucket on the temporarily inactive or returning portion of the circumference of the wheel is supported above the plane of the race until it reaches the in-

clined end o of the track, when it descends into the housing at the head of the race and receives the impact of the flowing water. As the bucket nears the tail portion of the race its roller mounts the inclined end o' of the track, and the bucket is thereby gradually elevated until lifted clear out of the water, and at the same time the bucket following descends the inclined track portion o and is submerged. The bucket-carrying arms are adapted to move freely in a vertical plane to permit of this operation by reason of their pivotal connection with the hub g. It will thus be seen that as the buckets on the inactive or returning portion of the wheel are not submerged, but are supported wholly out of the water, the full impulse of the flowing water is taken advantage of in the most effective manner, while the objections incident to the ordinary type of submerged wheel—i. e., back pressure and the resistance opposed to the passage of the returning buckets through the water—are entirely avoided.

The bucket-carrying sections of the radial arms are securely tied and braced against lateral strain by a continuous series of braces s, which respectively connect each adjoining pair of arms. Each brace consists of a sleeve or cylinder t, provided at one end with an arm u, pivoted to one of the radial arms, and a rod u', fitted to slide in the opposite end of the cylinder, said rod being pivoted at its outer end to the next adjoining radial arm and formed at its inner end with a head. A stiff tension-spring w inclosed in the cylinder bears against the head v and normally forces the rod inwardly. A simple and effective compensating bracing connection is thereby provided, which prevents undue lateral movement of the radial arms, while allowing said arms to have ample freedom of movement in a vertical plane to compensate for the ascension and descension of the buckets.

In the embodiment of my invention disclosed in Figs. 11 and 12 the construction of the wheel is modified by rigidly attaching the arms H' to the hub and mounting the buckets M' in a different manner. The track and race are, however, essentially the same in form and construction, the race being provided in its bottom with a groove o², connecting the inclined ends o o' of the track. Each bucket is supported from its wheel-arm by hangers constructed in two sections jointed centrally, as at y, and pivoted at their inner ends z to the arm, so as to allow the bucket to move freely in a vertical plane. The rollers n' are also mounted upon the front wall of the bucket and run upon the trackway in advance thereof, and the wheel-arms are connected by rigid brace-rods s'. In operation the buckets in moving through the segmental housing of the race exert a pull on the arms, and the wheel is thereby caused to revolve.

Although I have specifically described the construction and relative arrangement of the

several elements of my invention, I do not desire to be confined to the same, as such changes or modifications may be made as clearly fall within the scope of the invention without departing from the spirit thereof.

Having thus fully described my invention, what I claim as new and useful, and desire to secure by Letters Patent, is—

1. In a turbine water-wheel, the combination of a race having vertical parallel walls deflected outwardly at the junction of the head and tail portions thereof to form a segmental box or housing, a vertical shaft arranged exteriorly of the race adjacent to the deflected portion of its inner wall, a nearly circular horizontal track supported concentric with the shaft above the plane of the race and having inclined terminals leading down into said housing, and a wheel mounted on the shaft and provided with radial arms carrying buckets pivotally mounted to swing independently in a vertical plane and having rollers adapted to traverse said track, substantially as described.
2. In a turbine water-wheel, the combination of a race having vertical parallel walls deflected outwardly at the junction of the head and tail portions thereof to form a segmental box or housing, a vertical shaft arranged exteriorly of the race adjacent to the deflected portion of its inner wall, a wheel mounted on the shaft and provided with a series of radial arms pivoted to swing independently in a vertical plane, buckets carried by said arms and one of the buckets only being normally submerged in the race, and means for elevating and supporting the buckets and arms on the exterior of the race, substantially as described.
3. In a turbine water-wheel, the combination of a race provided with a segmental box or housing, a nearly circular track arranged exteriorly of the race and above the plane thereof and having its ends leading down into said housing, and a wheel provided with a series of radial arms pivoted to swing independently in a vertical plane and each composed of two sections adjustably connected, and buckets mounted on the outer sections of the arms and carrying rollers adapted to traverse said track, substantially as described.
4. In a turbine water-wheel, the combination with a race provided with a segmental box or housing, of a nearly circular track supported exteriorly of the race and having its ends leading down into said housing, and a wheel mounted exteriorly of the race and provided with a series of radial arms pivoted to swing independently in a vertical plane, a concentric series of braces each pivotally connected to two adjoining arms and adapted to oppose a resistance to the lateral movement of the arms while allowing them to have free vertical movement, and buckets mounted on

the arms and carrying rollers adapted to traverse the track, substantially as described.

5. In a turbine water-wheel, the combination with a race provided with a segmental box or housing, of a vertical shaft arranged exteriorly thereof, a track supported concentric with the shaft and having its ends leading down into said housing, and a wheel mounted on the shaft and provided with a series of radial arms each composed of a pivoted coupling-section and a bucket-carrying section adjustably connected therewith, a concentric series of compensating braces connecting the arms and each comprising a cylinder pivoted to one arm, a headed rod sliding therein and pivoted to the next adjoining arm, and a spring surrounding said rod and bearing against the head thereof to normally press the rod inwardly, and buckets mounted upon the outer ends of the said bucket-carrying sections of the arms and carrying rollers to traverse the track, substantially as described.

6. In a turbine water-wheel, the combination with a race provided with a segmental wheel box or housing, of a nearly circular track supported exteriorly of the housing above the race and having its opposite ends leading down thereinto, and a wheel comprising a hub, a series of radial arms pivoted thereto, each arm being formed of two sections united by an adjustable coupling, a series of yielding compensating braces pivoted to the outer sections of the arms, and each having a movable member held under spring-tension, and buckets mounted on the arms and carrying rollers adapted to traverse the track, substantially as described.

7. In a turbine water-wheel, the combination of a race having vertical parallel walls deflected outwardly to form a segmental wheel box or housing, a vertical shaft arranged exteriorly of the race adjacent to the deflected portion of its inner wall, a nearly circular inwardly inclined track approximately L-shaped in cross-section and supported concentric with the shaft above the plane of the race and having its ends leading down into said housing, the vertical web of said track being provided with a relatively narrow horizontal flange and the track proper with a vertical flange at the inner edge thereof, a wheel mounted on the shaft and provided with a series of pivoted radial arms adjustable as to length, and buckets carried by said arms, each bucket having its outer end wall m stepped to form recessed faces m' m'', and a roller carried by the said face m' to traverse the track, substantially as described.

In testimony whereof I affix my signature in presence of two witnesses.

NEWTON K. BOWMAN.
